SHEET CATCHING AND STACKING
MECHANISMHarry W. Theiss, Louisville, Ohio, assignor to
Continental Steel Corporation, Kokomo, Ind.,
a corporation of Indiana

Application November 28, 1938, Serial No. 242,760

12 Claims. (Cl. 271—80)

The mechanism of the present invention is designed to stack a multiplicity of metal sheets in column form as they are delivered singly in progressive relation from a furnace, tank, or other apparatus within which they have been treated; and the object of the present invention is to make provision for the linear advance of the sheets to the point of deposit and for their release at this point so that they will fall uniformly in position 10 in the building up of a stack to the desired dimensions.

In order to deposit the sheets from above, it is necessary to provide mechanism which will not interfere with the dropping of the sheets at the 15 point of deposit, and for this purpose a series of magnetic rolls is employed which serve to suspend the sheets from above, and this in conjunction with automatic means for sequentially demagnetizing certain of the rolls permits the sheets to 20 be adequately suspended during the required interval and deposited singly upon the top of the stack without the provision of any underlying support.

Further objects and details will appear from 25 the description of the invention in conjunction with the accompanying drawing, wherein,

Figure 1 is a sectional view of the apparatus embodying the features of the present invention;

Fig. 2 is a top or plan view thereof; and

Fig. 3 is a wiring diagram of the magnetic rolls and circuits for controlling them.

The metal sheets X, in the embodiment of the invention here shown, are discharged from a heating furnace 10 by the action of discharge 30 rolls 11, but in view of the fact that the present invention nowise relates to any preliminary treatment of the sheets it is not deemed necessary to describe the furnace in detail. It will also be understood that the present mechanism may be 35 associated with cleaning or pickling tanks, or other appliances or apparatus for treating or manipulating the sheets in any desired manner.

The discharge rolls 11 are aligned with upper and lower spaced guide bars 12 formed of micarta, 40 which afford a guideway or channel for the forward advance of the sheets to a permanently magnetized overhead roll 13 which constitutes the first of a series of aligned rolls for advancing the sheets to the point of deposit. The remainder 45 of the series of rolls comprise the forward group consisting of the rolls 14 and 15, and the rear group consisting of the rolls 16, 17, 18 and 19. These two groups of rolls are wired, as later will be disclosed, for temporary magnetization, so that 50 as the sheets are advanced certain of the rolls

may be demagnetized at the proper intervals to effect deposit of the sheets on the stack 20.

In order to adequately guide the sheets under the series of rolls, intervening overhead guide bars 21 of micarta are provided between each of the magnetizable rolls and in alignment with the upper guide bars 12, gaps being afforded between the guide bars for the exposure of the under surfaces of the magnetized and magnetizable rolls to a slight degree, so that positive contact with the 10 magnetized surfaces may be effected. The guide bars, however, serve as strippers to prevent undue adhesion of the sheets upon the magnetic surfaces and to insure an even forward advance of the sheets while suspended from above. It will 15 be noted that the ends of the guide bars adjacent the surfaces of the rolls are beveled so that no appreciable gaps are presented.

Intermediate the rolls 17 and 18 is a limit switch 22 provided with a pivoted roller 23 which 20 is elevated by and rides upon the surface of an advancing sheet, and is pivoted to drop to a lower position when the trailing edge of the sheet passes the roller.

Each of the rolls 13 to 19 inclusive contains a 25 magnet coil as 13^a, 14^a, 15^a, 16^a, etc. Coil 13^a is connected across the power line 30. Coils 14^a and 15^a are connected at one end through leads 31 and 32 to one side of the electric power line 30 and at the other end through a lead 33 to one 30 side of the switch 22, the opposite side of this switch being connected to the other side of the power line. Likewise, the magnet coils 16^a, 17^a, 18^a and 19^a are connected at one side in parallel through a lead 34 to one side of the power line 35 and at the other side through a lead 35 to one side of the switch 24, the other side of the switch being connected to the opposite side of the power line.

Thus, as the leading edge of a sheet advances, 40 it lifts the roller 23 thereby opening the switch 22 which is normally closed by the weight of the roller. This demagnetizes the coils 14^a, 15^a and permits the trailing end of the sheet to drop away from the rolls 14, 15 as shown in Fig. 2 while 45 it is still held by the later rolls 16, 17, 18, 19. The instant the sheet lifts the roller 25, the switch 24 opens thereby demagnetizing the remaining rolls causing the sheet to be dropped on the stack 20. The rollers 23 and 25 then serve to again 50 close the switches 22 and 24.

In order to properly align the sheets as they are deposited, a barrier plate 26 is provided, against which the forward edges of the sheets will abut as they are deposited by the rolls. The rolls are 55

all driven at a uniform feeding speed through the provision of suitable sprocket driving mechanism 21 actuated from a common source of power 28, which mechanism, however, need not be described in detail.

Operation

In use, the sheets delivered singly by the discharge rolls 11, or in any other suitable manner, are advanced through the guideway afforded by the bars 12 to the permanently magnetized roll 13, and as soon as contact is effected with this roll the forward edge of the sheet will be held elevated without underlying support. The roll 13 continues the advancement successively to the rolls 14, 15, 16 and 17, and as soon as the sheet advances beyond the roll 17 it will engage the roller 23 of the limit switch 22 and lift the same slightly, which movement is availed of to 10 actuate the limit switch and demagnetize the first group consisting of the rolls 14 and 15. This allows the trailing edge of the sheet to sag downwardly to some extent, as indicated, to afford an easy clearance for the following sheet. At 15 this stage the advancement of the sheet is continued by the rolls 16 and 17, and thereafter also by the rolls 18 and 19, so that at this stage the sheet will have magnetic contact with all four rolls in the second group, but as soon as the 20 forward edge of the sheet engages and lifts the roller 25 of the limit switch 24, this will actuate the limit switch and demagnetize the four rolls constituting the second group, which permits the sheet to drop freely to the top of the stack, although at this stage there will be sufficient forward momentum to cause the sheet to slide sufficiently to contact the barrier plate 26 which aligns all of the sheets in uniform vertical relation and serves to maintain the stack evenly 25 during the accumulation of the sheets.

40 The apparatus as a whole is so constructed that the sheets at all times during the advancement will be held in magnetic contact with at least two rolls, so that an adequate grip will be afforded to advance the sheets evenly and certainly without sidewise slewing or deflection; and by the movement of the limit switches, and by actuating the rolls constantly at a predetermined feeding speed, provision is made for the uniform deposit of the sheets with due allowance for the forward thrust of the sheets after 45 final release from the magnetic rollers and due to the momentum previously acquired.

Although the invention has been described with particularity as to detail, it is not the intention, unless otherwise indicated in the claims, to limit the invention to the specific form shown, since modifications may be introduced without departing from the spirit of the invention.

I claim:

60 1. In sheet stacking mechanism of the class described, the combination of a plurality of magnetizable rolls arranged in overhanging relation to the sheet feeding plane and adapted in sequence to magnetically engage, suspend and advance the sheets to the point of deposit, automatic means located at an intermediate point and actuated by the arrival of a sheet at said point for demagnetizing certain of the magnetizable rolls while leaving other rolls magnetized, and automatic means located adjacent the point of final deposit and actuated by the arrival of a sheet at that point for demagnetizing the remaining rolls to effect release and deposit of the sheets.

70 2. In sheet stacking mechanisms of the class

described, the combination of a plurality of magnetizable rolls arranged in overhanging relation to the sheet feeding plane and adapted in sequence to magnetically engage, suspend and advance the sheets to the point of deposit, automatic means actuated by the arrival of a sheet for demagnetizing certain of the rolls to effect release and deposit of the sheet, and a stop barrier located adjacent the point of deposit for arresting the advance of the sheets after release by the magnetizable roll in effecting an even stacking of the sheets.

3. In sheet stacking mechanism of the class described, the combination of a plurality of magnetizable rolls arranged in overhanging relation to the sheet feeding plane and adapted in sequence to magnetically engage, suspend and advance the sheets to the point of deposit, automatic means located at an intermediate point and actuated by the arrival of a sheet at said point for demagnetizing certain of the magnetizable rolls while leaving other rolls magnetized, automatic means located adjacent the point of final deposit for demagnetizing the remaining rolls to effect release and deposit of the sheets, and a stop barrier located adjacent the point of deposit for arresting the advance of the sheets after release by the magnetizable roll in effecting an even stacking of the sheets.

4. In sheet stacking mechanism of the class described, the combination of a sheet supporting and advancing means, a series of magnetizable rolls having their lower feeding surfaces in aligned relation, means for rotating the rolls uniformly to advance the sheets in processional relation, means actuated by the arrival of a sheet at a predetermined position beyond the sheet supporting and advancing means for demagnetizing the magnetizable rolls and effecting deposit of the sheets, and a fixed barrier for arresting the forward advance of the sheets after release in effecting an even stacking of the sheets.

5. In sheet stacking mechanism of the class described, the combination of a sheet supporting and advancing means, a series of magnetizable rolls having their lower feeding surfaces in aligned relation, means for rotating the rolls uniformly to advance the sheets in processional relation, means actuated by the arrival of a sheet at a predetermined position beyond the sheet supporting and advancing means for demagnetizing the magnetizable rolls and effecting deposit of the sheets, and aligned guide means interposed between the rolls in position to expose the lower surfaces of the rolls and direct the sheets forward in an even line of advance.

6. In sheet stacking mechanism of the class described, the combination of a sheet supporting and advancing means, a series of magnetizable rolls having their lower feeding surfaces in aligned relation, means for rotating the rolls uniformly to advance the sheets in processional relation, means actuated by the arrival of a sheet at a predetermined position beyond the sheet supporting and advancing means for demagnetizing the magnetizable rolls and effecting deposit of the sheets, a fixed barrier for arresting the forward advance of the sheets after release in effecting an even stacking of the sheets, and aligned guide means interposed between the rolls in position to expose the lower surfaces of the rolls and direct the sheets forward in an even line of advance.

7. In sheet stacking mechanism of the class described, the combination of a magnetic sheet

supporting and advancing means located in the advanced feeding position, a series of magnetizable rolls located progressively beyond the sheet supporting means and comprising two groups 5 consisting each of a plurality of magnetizable rolls, automatic switch means actuated by the arrival of a sheet at a point beyond the first roll of the second group for demagnetizing the rolls of the first group to release the trailing end of 10 a sheet while the leading end is in contact with a portion of the second group, and automatic means located beyond the last roll of the second group and actuated by the arrival of the leading edge of a sheet at that point to demagnetize 15 the rolls of the second group to effect release and deposit of the sheet.

8. In sheet stacking mechanism of the class described, the combination of a magnetic sheet supporting and advancing means located in the advanced feeding position, a series of magnetizable rolls located progressively beyond the sheet supporting means and comprising two groups 20 consisting each of a plurality of magnetizable rolls, automatic switch means actuated by the arrival of a sheet at a point beyond the first roll of the second group for demagnetizing the rolls of the first group to release the trailing end of a sheet while the leading end is in contact with a portion of the second group, automatic 25 means located beyond the last roll of the second group and actuated by the arrival of the leading edge of a sheet at that point to demagnetize the rolls of the second group to effect release and deposit of the sheets, and a fixed barrier for 30 arresting the forward advance of the sheets after release in effecting an even stacking of the sheets.

9. In sheet stacking mechanism of the class described, the combination of a plurality of spaced magnetic means arranged in a desired line of 40 advance for suspending a ferrous sheet, means for advancing the sheet, means for demagnetiz-

ing certain of the magnet means as the sheet advances to release the trailing end of the sheet while the leading end is held by other magnetic means, and means for demagnetizing said other magnetic means to effect release of the sheet and 5 stacking thereof at a desired point of advance.

10. In sheet stacking mechanism of the class described, the combination of a plurality of spaced magnetic means arranged in a desired line of advance for suspending a ferrous sheet, 10 means for advancing the sheet, means operable by the sheet for demagnetizing certain of the magnet means as the sheet advances to release the trailing end of the sheet while the leading end is held by other magnetic means, and means oper- 15 able by the sheet for demagnetizing said other magnetic means to effect release of the sheet and stacking thereof at a desired point of advance.

11. The method of handling and stacking ferrous sheets comprising moving one sheet at a 20 time beneath the first of a series of parallel rolls, magnetizing these rolls in advance of the leading edge of the sheet to support the sheet as it advances, progressively demagnetizing the rolls as the sheet advances so as to release the 25 trailing end of the sheet while the leading end is supported, and demagnetizing the remaining rolls to release the sheet entirely when it has advanced to a predetermined point.

12. The method of handling and stacking ferrous sheets comprising advancing the sheets while held suspended at spaced progressive points in the line of advance by magnetic flux, progressively stopping the magnetic flux at certain points as the sheet advances to drop the trailing edge of 30 the sheet while the leading edge is held suspended, and stopping all magnetic flux when the sheet has advanced to a predetermined point to 35 effect complete release and deposit of the sheet.

HARRY W. THEISS.
